UNITED STATES PATENT OFFICE

GEORGE R. RICH, OF BATTLE CREEK, MICHIGAN

VALVE TAPPET

Application filed November 12, 1928. Serial No. 318,743.

This invention relates to valve tappets for internal combustion engines, and its principal object is to increase the efficiency of such tappets and to overcome certain objectionable features now present therein. It is well known that valve tappets employ an adjustment stud for engagement with the stem of the valve with which the tappet is used, and that considerable difficulty has been experienced in forming the threaded bore for the adjustment stud in true alignment with the axis of the tappet, the result being that frequently the stem is tilted slightly and the contacting end of the stud instead of being at perfect right angles to the axis of the stem is slightly inclined, so that its entire end does not contact with the end of the valve stem.

Furthermore, it has been observed that when the lock nut, usually employed in connection with the adjustment stud, is screwed up tightly against the end of the tappet stem, the wall surrounding the threaded portion thereof becomes bulged outwardly, and although this bulged portion is very slight, yet it interferes with the perfect operation of the tappet and the valve, because valve tappets are fitted fairly close in the guides in which they are held and the bulged portion causes the stem of the tappet to bear unequally in the guide and prevents it from moving freely therein because of the friction between the bulged portion and the guide. In accordance with the present invention, I have overcome these various difficulties and have provided a tappet wherein the adjustment stud is held in exact co-axial alignment with the tappet and the possibility of bulging is eliminated.

With these and other objects and advantages in view, the invention consists in a valve tappet having an adjustment stud threadedly secured in the head portion of the tappet and extending out through an opening in the stem end. It further consists in a tappet in which the bore in the stem end of the tappet is unprovided with any screw threads for the adjustment stud, whereby the possibility of bulging, when pressure is applied thereto by a lock nut, is eliminated. It further consists in a tappet having a re-

inforcing element for the neck portion of the head of the tappet.

It further consists in the several novel features hereinafter fully set forth and claimed.

The invention is clearly illustrated in the drawing accompanying this specification in which—

Figure 1 is a central longitudinal section through a valve tappet embodying a simple form of the present invention;

Fig. 2 is a view similar to Fig. 1 with the adjustment stud and lock nut removed therefrom;

Fig. 3 is an end view of the tappet looking at the head portion thereof;

Fig. 4 is a horizontal section taken on the line 4—4 of Fig. 1; and

Fig. 5 is a central longitudinal section through a slightly modified form of the invention.

Referring to said drawing, the reference character 6 designates a hollow stem, preferably formed of steel, and 7 designates the cam contacting head of the tappet which, in accordance with one form of the invention, may be formed of cast iron. The head portion is cast with a neck 8 which fits tightly in the upper end of the hollow stem 6 and is secured thereto by a close fit, or it may be spot welded thereto as desired. The neck 8 is formed with a shoulder 9 against which the extreme end of the hollow stem engages. The wall of the main portion of the stem may be made relatively thin in order to obtain lightness, and the wall 10 at the end portion of the tappet opposite the head 7 is thicker than the wall of the main portion and is flattened at two sides for the reception of a wrench or other tool.

The stem portion is preferably formed of a steel rod bored out to provide the thin walled main portion, and also bored out at the end opposite the head to form a stud receiving unthreaded bore 11. The neck of the head portion 7 is bored and tapped as at 12 for the reception of the threaded end 13 of an adjustment stud 14, and said adjustment stud extends out through the bore 11 and is provided with a threaded portion 15 adjacent its head 16, which threaded portion 15

is of approximately the same diameter as the diameter of the unthreaded bore 11 and fits nicely thereon. The remainder of the stem portion beyond the threaded part 15 is preferably reduced in diameter, whereby it may be readily inserted through the bore 11 in assembling the parts. The usual lock nut 17 is threaded upon the threaded part 15 of the adjustment stud and is arranged to bear against the extreme end of the tappet stem.

It is to be observed that the threaded part 15 of the adjustment stud does not engage in any threaded part in the wall 10 of the tappet stem, and, consequently, when the lock nut is screwed up tight, there is no tendency for the portion of the stem around the bore 11 to bulge outwardly. Furthermore, inasmuch as the effective connection between the adjustment stud and tappet is at the head end thereof, the threaded part 15 will center itself perfectly in the bore 11 in which it fits.

In tappets where the threaded connection between the stem and adjustment stud is made at the end of the stem, the inclined sides of the threads of the adjustment stud tend to climb up the inclined sides of the threads in the tappet stem when the lock nut is screwed up tight against the end of the tappet stem, thereby causing the wall of the tappet stem around the threaded part to bulge outwardly. This is entirely eliminated where the threaded connection is between the adjustment stud and the head end of the tappet. Furthermore, the adjustment stud being formed of steel, it reinforces the more fragile cast iron held at the neck portion thereof.

In the form of the invention illustrated in Fig. 5, the major portion of the head portion 7^a is formed of steel, and the cam contacting face 7^b is composed of cast iron or white iron integrally united with the main portion of the head by fusing the same therewith. Otherwise, the construction of the tappet is substantially the same as that shown in the other figures.

The end faces of the tappet and the valve contacting end of the adjustment stud should be accurately ground at right angles to the axis thereof, which may be done with suitable grinding machinery, and the valve contacting end of the adjustment stud should be hardened. This may be done by friction grinding the end face of the head 16 and quickly quenching the same.

More or less variation of the exact details of construction is possible without departing from the spirit of this invention. I desire, therefore, not to limit myself to the exact form of the construction shown and described, but intend, in the following claims to point out all of the invention disclosed herein.

I claim as new, and desire to secure by Letters Patent:

1. A valve tappet comprising an axially bored unthreaded tappet stem, a head on one end of said stem, an adjustment stud threadedly secured in said head and protruding from the end of the stem, said adjustment stud having a valve contacting head on its outer end, and there being screw threads on said adjustment stud adjacent its head for a lock nut, and said last mentioned screw threaded portion fitting in an unthreaded portion of the bore of the stem, and a lock nut on the threaded portion of the adjustment stud adjacent its head and arranged to impinge against the unthreaded end of the stem. 70

2. A valve tappet comprising a hollow tappet stem having an unthreaded bore at one end and a separately formed cam contacting head portion upon its other end, and an adjustment stud having a head and a threaded portion for a lock nut adjacent its head portion, said threaded portion being contained in the unthreaded bore of the stem and said stud being provided with a threaded end portion threadedly secured in the tappet head, and there being a lock nut on the threaded portion of the stud adjacent its head and adapted to impinge against the unthreaded end of the stem. 80

3. A valve tappet comprising a hollow stem having an unthreaded bore at one end, a separate cam contacting head having a neck portion secured in the other end of the stem, 100 said neck portion having a threaded bore therein, an adjustment stud having a valve contacting head on one end and formed with lock nut receiving screw threads adjacent said head, the other end of said adjustment stud being formed with screw threads engaging in the threaded bore of the neck of the tappet head, and a lock nut on the threaded portion of the stud adjacent its head and adapted to impinge against the unthreaded end of the stem. 105

4. A valve tappet comprising a hollow thin walled stem portion formed at one end with an axial unthreaded bore of less diameter than the internal diameter of the main portion of the stem, a separate cam contacting head having an internally threaded neck secured in the other end of the stem, an adjustment stud having a valve contacting head on one end and formed with a threaded portion adjacent said head fitting in the reduced unthreaded bore of the tappet stem, and the other end of said adjustment stud being threaded and engaging in the screw threads of the threaded bore of the tappet head, and a lock nut on the threaded portion of the stud adjacent its ends and adapted to impinge against the unthreaded end of the stem. 115

5. A valve tappet comprising a steel stem 120

- portion axially bore throughout the major portion of its length to provide a thin wall and having an unthreaded bore at one end of reduced diameter and co-axial with the first mentioned bore, a cast iron cam contacting head having a neck fitting in and secured in the larger bore of the stem, said neck being bored and internally threaded, and an adjustment stud having a valve contacting head at 5 one end and formed with screw threads adjacent said head, a lock nut threadedly secured upon said threads of the adjustment stud and arranged to bear against the adjacent end of the stem, and the inner end of said adjustment 10 stud being of reduced diameter and having threads thereon engaging in the threads of the threaded bore in the neck of the tappet head.
